ALARM SYSTEM

Gerald G. N. Purcell, East Orange, N. J., assignor to American District Telegraph Company, New York, N. Y., a corporation of New Jersey

Application March 4, 1938, Serial No. 193,873

4 Claims. (Cl. 177—360)

This invention relates to a watchman's tour system wherein a factory or other premises is equipped with a number of signal transmitting stations so arranged that a watchman will make a predetermined tour of the premises and will operate the stations in a predetermined order within a given grace period whereby failure of the watchman to so operate the stations will be indicated at a remote control office.

The principal object of this invention is to simplify the watchman's compulsory tour system and yet increase the safety of the system by providing a number of different annunciation or control functions in a signal receiver from a number of non-coding transmitting stations using only a few conductors.

A further object of the invention is to provide in a watchman's tour system a plurality of tour transmitting stations, each station being directly supervised by a central station, as an improvement over prior systems wherein only certain stations are connected to the central station and intermediate stations merely perform a mechanical operation on the watchman's register to enable operation of the connected stations.

Another object of this invention is to provide a watchman's tour system wherein the transmitting stations do not transmit a code but merely polarize the transmission lines in such a manner that an indication is received at the central station.

A still further object of this invention is to provide a compulsory watchman's tour system wherein the proper sequential operation of the transmitting stations will polarize the transmission lines to produce signals individual to each transmitting station.

Another object of this invention is to provide an improved compulsory tour system wherein the watchman must visit the transmitting stations according to a predetermined sequence within a prescribed time limit and wherein failure so to do will result in a delinquency signal which indicates trouble and leads to an investigation thereof.

A further object of this invention is to provide a compulsory sequence watchman's delinquency system wherein all transmitting stations are electrically connected to the control equipment with a small number of conductors and using non-coding transmitters.

Further objects and advantages of this invention will appear from the following description of the preferred embodiment shown in the drawings, in which

Fig. 1 shows the transmitting stations and part of the control equipment of the watchman's tour system;

Fig. 2 shows selectors and an indicating device to be used in connection with Fig. 1;

Fig. 3 shows a watchman's transmitter device and the jacks for receiving the transmitter; and

Fig. 4 shows a modified form of receiver.

The preferred embodiment of this invention comprises a watchman's compulsory sequence delinquency system wherein the transmitting stations are all connected by wires to the control equipment as distinguished from prior systems of this nature in which some of the route stations are not actually connected to the control equipment but merely condition a watchman's register for operating other route stations which are electrically connected to the control equipment. This system provides a watchman's tour which is less vulnerable to attack than the prior mechanical tour systems.

Referring to the drawings, Fig. 1 shows transmitting stations I to XII which are connected by three wires to the control equipment, but, if desired, a system of more stations can be provided by using more wires, each station transmitting an individual signal. For instance, 24 stations require four wires, 40 stations require five wires, and 60 stations require six wires, or the stations can be further increased by increasing the number of wires polarized by each station. A one-wire alternating current supply is also necessary and therefore increases the number of wires in each case by one unless the power supply is picked up at or beyond the transmitting point. Each transmitting station comprises two sets of contacts and the watchman's transmitter comprises two dry plate rectifiers 4 and 5 with which he transmits the signals characteristic of each station. Numeral I of the drawings indicates one complete transmitting station. Station I, for example, is connected to a grounded alternating current supply 10 through conductor 11 and to the control equipment comprising relays 16, 17, 23 and 24 and rectifiers 14, 15, 19, and 20 by conductors 13 and 18 respectively. Station III is connected in a different manner to the control equipment through conductor 13, as mentioned above in connection with station I, and through conductor 25, rectifiers 26 and 28 to relays 27 and 29 respectively. Relays 16, 17, 23, 24, 27 and 29 are all normally energized and slow to release so that normally the armatures are pulled up and do not drop during the suppressed half wave. The armature 32 of relay 16 is connected from bat-

55

ter through its contact to conductor 36, contacts 62, 63, 64 and 65 of selector switch 100, Fig. 2, which is in turn connected to an indicator reset device such as shown in Patent No. 1,942,814 issued January 9, 1934, to R. M. Hopkins and which is located at a central office. The indicator reset device is a timing circuit which will produce a delinquency signal unless it is reset to its starting position as a result of the proper operation by the watchman of the route stations. Armature 40 of relay 17 completes a connection from battery through contact 41 and conductor 38 to contacts 66, 67, 68 and 69 of selector switch 100. Armature 45 of relay 23 is connected through contact 46 and conductor 48 to contacts 70 and 71 of selector switch 100, while armature 51 of relay 23 is connected through contact 52 and conductor 53 to contacts 75 and 79 of selector switch 100. The armature 56 of relay 24 is connected through contact 57 and conductor 50 to contacts 72 and 73 of selector switch 100, while armature 58 of relay 24 is connected through contact 59 and conductor 60 to contacts 76 and 80 of selector switch 100. Armature 95 of relay 27 is connected through contact 96 and conductor 97 to contacts 77, 81, 83 and 85 of selector switch 100 and armature 98 of relay 29 is connected through contact 99 and conductor 122 to contacts 78, 82, 84 and 86 of selector switch 100. The selector switch arms 61 and 74 are each connected to stepping relay 90 and interrupter contacts 91 as shown in the drawings. Relays 16, 17, 23, 24, 27 and 29 each operate armatures 30, 31, 42, 43, 55 and 55', which are connected in a trouble circuit 34.

It may be desirable to use in this system annunciators or recorders instead of the selector switch and indicator reset device for indicating the whereabouts of a watchman. As shown in Fig. 4 of the drawings, the annunciator or recorder coils 101 to 112 may be connected to the conductors 36, 38, 48, 50, 53, 60, 97 and 102. Thus, in a proprietary system, for instance, a chief watchman may observe the annunciator drops or the recorder tapes and thereby check the whereabouts of each watchman under his supervision.

The operation of the compulsory tour circuit is started when the watchman inserts his transmitting device 7, shown in Fig. 3, in the jacks 1 and 2 which are shown at station I, for instance. The watchman's transmitter device contains rectifiers 4 and 5 shown in station I. Insertion of the transmitting device connects the rectifier devices in series in each of the conductors 13 and 18 in order to operate the selector switch arms 61 and 74 in the proper sequence. Signals of particular polarity must be transmitted from each transmitting station. Therefore, the watchman's transmitter 7 is connected to the lines 13 and 18 in such a manner that the rectifiers contained therein will polarize both of the lines 13 and 18 positively. Since these lines are so polarized, relays 16 and 23 will release because of the fact that rectifiers 14 and 19 do not pass the positive half of the alternating current wave. The armatures 32 and 51 will therefore drop, closing a circuit from positive battery through conductor 36 and contact 62 to selector switch arm 61, through the stepping relay 90 and the indicator reset device in parallel through selector arm 74, contact 75, conductor 53 and armature 51, back to battery. The indicator reset device will be operated to prevent a delinquency alarm and the selector coil 90 will become energized, pull up its armature and break its own circuit at contacts 91, thus

completing its stopping function even while the transmitter 7 remains in the first station. Switch arms 61 and 74 advance to contacts 63 and 76 respectively. The circuit to coil 90 and to the indicator reset device is now open at contact 59 and the reset device starts a new timing cycle. As stated above, it is desirable and necessary that the watchman operate the tour stations in a predetermined sequence in order to prevent intruders or burglars from trying to operate the watchman's system. Thus the watchman must next operate station No. II. This station in effect sends a different signal by polarizing wire 13 positively and wire 18 negatively, whereas station I polarized both wires positively. Relay 16 will release its armature as before in connection with station I but since wire 18 is now polarized negatively relay 24 will drop its armature since rectifier 20 will not pass the negative half of the alternating current cycle. Thus a circuit is set up from armature 32 of relay 16 to conductor 36, contact 63 of switch 100, indicator reset device and relay 90 in parallel, switch arm 74, contact 76, conductor 60 and the armature 58 of relay 24. Thus the indicator reset device again prevents the delinquency alarm from operating and switch arms 61 and 74 are stepped to the next contacts. As the watchman progresses from station to station in the prescribed sequence, the switch arms 61 and 74 are stepped around to prevent a delinquency alarm, but if an intruder had attempted to operate the system, he would in all probability select the wrong sequence of stations. For example, if he attempted to operate the system and operated station VI instead of station III, lines 13 and 18 would be polarized negatively and relays 17 and 24 would drop their armatures since rectifiers 15 and 20 will not pass the negative half wave. However, it is found that the indicator reset device will not reset the alarm system because of the fact that armature 40 closes a circuit from battery through conductor 38 to contacts 66 to 69. However, the circuit is open at this point since switch arm 61 has not been stepped to these contacts by the proper sequence of transmission from the tour stations. Therefore, the indicator reset device has not been reset by the control equipment and will continue its operation to cause an alarm which will indicate to the central station operator that trouble of some sort has occurred in the protected premises. The indicator reset device will also operate if the signals from the respective transmitting stations are not sent within a predetermined time which would occur if the watchman is prevented from completing his tour.

The annunciator or recorder coils 101 to 112 are operated in a manner similar to the selector switch 100. For instance, when the watchman operates station I, he polarizes the lines 13 and 18 shown in Fig. 1 in such a manner that the relays 16 and 23 both drop their armatures. This sets up a circuit from positive battery through contact 33, line 36, annunciator or recorder 101, line 53, contact 52, to negative battery, thereby operating the annunciator 101. The remaining annunciators 102 to 112 are operated in the obvious manner as the watchman progresses from station to station of his prescribed tour. Obviously, the selector and indicator reset, the annunciators and the recorder coils may all be operated simultaneously or each of the elements may be used alone in the system.

In the event that a break or ground occurs on lines 13, 18 and 25, the trouble circuit 34 will

give an indication. Taking line 13, for example, a break or ground will release both relays 16 and 17 to close through their armatures 30 and 31 respectively the trouble circuit 34. The other lines 18 and 25 will operate their respective relays in a similar manner in the event that any break or ground occurs. The trouble circuit 34 may be adapted to operate a bell or any other indicating device.

This system is found to be the acme of simplicity in that it does not require coding devices; it provides individual supervision at a receiver of a plurality of tour stations, only a few wires are necessary and it is less vulnerable to attack than the conventional mechanical tour systems.

Various modifications of the system are possible, one of which may be to increase the number of stations by increasing the number of wires as indicated previously, or to increase the number of stations by increasing the number of wires polarized by each station, or the polarizing feature of the system may be used separately; each station polarizing only one wire.

I claim:

1. A signal system comprising a source of potential, a transmitting station and a plurality of lines connected thereto, said transmitting station including jacks and a portable key member comprising rectifier members adapted to be connected to said jacks for signaling over said lines.

2. In a signal system, a source of alternating current, a plurality of conductors connected thereto, jacks connected to said conductors, a plug member adapted to be inserted in any group of said jacks, said plug member including a plurality of rectifiers adapted to be connected to said jacks for signaling over said conductors.

3. A watchman's signal system comprising a plurality of transmission lines, a source of alternating current common to said lines, a plurality of transmitting stations, each station being connected to at least two of said lines, a plurality of rectifiers adapted to be connected to said lines at each station, at least two pairs of contacts at each station, said rectifiers being connected to said contacts at each station in such a manner that the lines are polarized differently at each station, a receiving station, a pair of normally energized polarized relays connected to each transmission line, contacts operated by each relay and one or more selector switches connected to said contacts and adapted to be operated upon operation of said contacts.

4. A watchman's signal system comprising a plurality of transmission lines, a source of alternating current common to said lines, a plurality of transmitting stations, each station being connected to at least two of said lines, a plurality of rectifiers adapted to be connected to said lines at each station, at least two pairs of contacts at each station, said rectifiers being connected to said contacts at each station in such manner that the lines are polarized differently at each station, a receiving station, a pair of normally energized polarized relays connected to each transmission line, contacts operated by each relay and one or more selector switches connected to said contacts and adapted to be operated upon operation of said contacts and an indicator reset device connected to and operated by said selector switch.
